CLAIM

We claim, the ornamental design for a LED of side view type, as shown and described.

DESCRIPTION

FIG. 1 is a front perspective view of a LED of side view type, showing our new design;

FIG. 2 is a front elevational view of the LED of side view type of FIG. 1;

FIG. 3 is a rear elevational view of the LED of side view type of FIG. 1;

FIG. 4 is a left side elevational view of the LED of side view type of FIG. 1;

FIG. 5 is a right side elevational view of the LED of side view type of FIG. 1;

FIG. 6 is a top plan view of the LED of side view type of FIG. 1;

FIG. 7 is a bottom plan view of the LED of side view type of FIG. 1;

FIG. 8 is a cross-sectional view of the LED of side view type taken along line 8—8 in FIG. 2; and,

FIG. 9 is a bottom and rear perspective view of the LED of side view type of FIG. 1.

The broken lines shown in the figures are for illustrative purposes only and form no part of the claimed design.
